UNITED STATES PATENT OFFICE

2,553,153

PICKER STICK

Ervin A. Towns, Cambridge, Mass.

Application January 21, 1949, Serial No. 71,789

1 Claim. (Cl. 139—157)

1

My present invention relates generally to picker sticks for use in looms, and more specifically to a novel and improved picker stick construction combining the features of a permanent base portion and a replaceable upper portion, and further characterized by the inclusion of a wear-resisting picker-engaging element.

In the manufacture of picker sticks it is well established that for the most satisfactory performance it is preferable to have the upper portion of each stick adapted for resilient or "whipping" action and the base or lower portion possessing the properties of strength, rigidity, and durability. Therefore, in an effort to construct such articles in conformity with the above principle, picker sticks have been formed entirely of wood or metal, or in combinations of both.

In this connection, the completely wooden picker stick has proven objectionable chiefly because of excessive breakage and a limited operating life due to the severe strains to which it is constantly subjected. The wholly metal picker stick has often been found to be excessively heavy and, of course, does not possess the important feature of resiliency.

The combination wood-and-metal picker sticks have heretofore embodied a number of different forms, but the majority of these have encountered such practical difficulties as lack of balance, effective length of each material, method of uniting the two, added cost, replacement intricacies, and the like.

The main object of my invention, therefore, is directed to obviate the above briefly outlined difficulties by providing an efficient picker stick combining the features of resiliency and strength in effective association, which may be incorporated in any standard loom.

Another chief object of my invention pertains to the novel construction of the picker stick so as to assure long life and infrequent replacement to the parts thereof by providing a lower permanent metal base or socket portion adapted to be pivotally connected with the loom frame, and with means such as a projection or web in said base to engage the lower end of an upper resilient shuttle-actuating portion in interlocking association, especially arranged for easy and quick assembly and detachment.

A further prime object of my invention resides in the particular design of the metallic socket portion, including an interlocking rib construction which affords an extremely strong union with the lower end of the stick portion, thus imparting thereto great strength and support at

2

the point of severest strain without in any way impairing the inherent resiliency of its upper end.

A still further important object of my invention is the provision of picker-engaging means in the upper stick portion in the form of a wear-resisting plastic element which is impervious to the usual twisting strains involved, thereby assuring a longer degree of life to such stick portion. 5 Such element may be an insert or an addition, and has the important function of reinforcing the edges of the stick, thus insuring firm fitting with a drop box picker.

Further objects, advantages, and details of construction will be hereinafter more fully pointed out in the accompanying description and more clearly defined in the appended claim.

Referring now to the drawings, wherein I show preferred embodiments of my invention:

20 Fig. 1 is a side elevational view of my invention with the stick portion broken away, showing the socket portion formed of light metal, such as aluminum, magnesium, or synthetic plastic, with or without a reinforcing core.

25 Fig. 2 is an edge view of the same;

Fig. 3 is a cross-sectional view on the line 3—3 of Fig. 1;

Fig. 4 is a perspective view illustrating the interlocking lower end of the upper stick portion;

30 Fig. 5 is a side elevational view of a modified form of my invention, having the stick portion broken away, showing the socket portion formed of heavy metal, such as steel;

Fig. 6 is an edge view of the same;

35 Fig. 7 is an edge view of the interlocking end of the upper stick portion for association with the socket portion shown in Fig. 5;

Fig. 8 is a side elevational view, in reduced scale, of my complete picker stick of the form shown in Fig. 5, including a picker insert.

40 Fig. 9 is a sectional detail view of the top of the upper stick portion, illustrating the synthetic plastic insert feature.

Fig. 10 is a fragmentary side elevational view, 45 in reduced scale, showing a modification of an upper stick portion including a picker-engaging attachment.

In the drawings, referring particularly to Figs. 1 thru Fig. 4, 10 designates generally the upper stick portion of my improved picker stick which is made of any usual material having inherent resilient properties, such as hickory, laminated wood or the like, and is constructed, preferably, rectangular in cross-section and tapered towards 50 its smaller top end. The bottom section 11 of the

stick portion 10 is provided on each of its side edges with a longitudinal groove 12 and across its end edge with a connecting transverse groove or notch 14. The grooves 12-12 are either straight or suitably tapered, as shown in the drawing, from a desired depth at the bottom until substantially flush with the edge at the top, and, if desired, may be preferably rounded at the points of connection with each end of the notch 14. This cooperating lengthwise tapered construction provides an effective wedgingly interlocked connection between the top wooden portion and bottom metal portion, and is of importance in this type of two-part picker stick, providing speedy removal and replacement.

The lower socket portion or base member of my picker stick is designated generally at 20 and comprises a casting of some suitable light metal or any alloy thereof, such as aluminum, having a suitable bottom part 21 formed with a reinforced opening 22 therethru for pivotal attachment to the frame of the loom and, if desired, with a lug element or hook 43 for association with a standard heel strap.

Above said part 21 extends my specially designed, substantially rectangular interlocking framework consisting of a base 23, a pair of side arms 24-24 upstanding therefrom, inner ribs 25-25 formed on said arms 24-24 and merging into a web 26 on the base 23, and a pair of top reinforcing braces 27-27. The ribs 25-25 are widest at their bottom ends and gradually taper toward the arms 24-24 until such ribs 25-25 terminate substantially flush therewith at the extreme top thereof.

In assembling the upper portion 10 with the socket 20, it will be apparent that the same can be effected speedily and simply by sliding the grooves 12-12 on each edge of the bottom section 11 on the ribs 25-25 until the notch 14 seats on the web 26.

Thus assembled, a strong, interlocking and stress-reinforced and interfitting union between the portions 10 and 20 is provided, and, if desired and as shown in Figs. 1, 2 and 3, I may further strengthen my picker stick by securing these portions 10 and 20 by any suitable means such as a headed bolt 28 inserted thru cooperating openings thru the arms 24-24 and a hole bored in alignment therewith through the wooden section 11 as indicated at 15, Fig. 4, and secured by tightening of a nut 30.

In use, my picker stick is particularly efficient. The metal socket 20, being practically indestructible, is permanently pivoted on the loom frame in the usual manner thru the opening 22. When the lower part 11 of the stick portion 10 is fully seated within the interlocking construction of the socket frame and the nut 30, it will be found that the reinforcing braces 27-27 will provide positive and balanced support to the stick portion at the point of greatest strain, thus preventing undue wear to such stick portion and assuring added life and long wear to the same.

Referring specifically to the modification shown in Figs. 5 thru 9, wherein I show a socket portion formed of heavier metal, such as steel, and a stick portion having incorporated therein a specially designed insert to prevent damaging wear thereto about the area subjected to repeated twisting contact with the usual loom picker.

From my experiments in this art, I have found that where a steel casting is used for the socket portion, the heavier metal of itself insures ad-

ditional strength and greater support so that a simpler interlocking arrangement may be satisfactorily employed with equally proficient results. And I have also discovered in this form that the points of stress and balance in relation to the cooperating stick portion are distinct and different, as will be hereinafter shown.

In this modification I have illustrated a socket portion 40 in the form of a steel casting, or any alloy thereof, having a base 41 with a reinforced opening 42 therethru for loom-engagement, and a novel hook or lug 43 projecting from the heel thereof for heel strap attachment. Flaring slightly from said base 41 into an open frame-like section 44 is the upper part of the socket 40, which comprises side arms 45-45, reinforced upper cross-braces 46-46, and a lower upstanding web element 47. The open section 44 is of suitable width and thickness to permit the penetration therein of the lower portion 51 of a stick portion 50, the end of which portion 51 is appropriately notched, as at 52, to interlock with the web 47.

To prevent the stick portion 50 from jumping out of the socket 40 during the operation of the loom, I have provided a headed bolt 53, which is easily slid thru suitable openings drilled thru the side arms 45-45 and the lower portion 51, and secured by the tightening of a nut 54. As shown in Fig. 5, I prefer in this modification to locate the bolt 53 substantially centrally of the interlocked section, which constitutes a point of severe stress and, thus, one which needs reinforcing.

In the loom operation, as the picker stick oscillates in receiving and throwing the shuttle, the usual picker or drop-box picker which is attached on the picker stick adjacent the top thereof, tends to subject this upper stick surface to such severe twisting strains that the edges thereof are often worn away in a short period of time, thereby necessitating a replacement.

To obviate this difficulty I prefer to provide an insert 55 adjacent the top of the stick 50 suitably morticed therein, and appropriately formed of a wear-resisting synthetic plastic material, thus giving added strength and longer life to the picker-engaging portion of the stick.

Referring to Fig. 10, I show a modified form of picker-engaging element, particularly adapted for use with a drop-box picker. Herein my stick member is designated generally as 60 and includes an upper end section 61 suitably cut out or reduced in exact proportion to the dimensions of a wear-resisting reinforcing strip 62 formed of synthetic plastic material, fibre, or the like. In uniting the strip 62 to the stick end 61 I may employ any suitable means, such as a removable bolt or pin 63 adjacent the top and a metal band or collar 64 adapted to be slipped over the top and wedged adjacent the bottom, and there further secured by an appropriate rivet 65.

As thus constructed, the dimensions of the top 65 of the stick 60 are suitably proportioned to engage the standard opening in the drop box picker and the reinforcing strip so positioned as to absorb all the twisting and strains during the shuttle-receiving and throwing operations, thus eliminating the usual wear and breaking away of the upper picker stick edges.

Although I have shown the base parts 21 and 41 as being solid portions, I may prefer to lighten or decrease the weight of the same by having openings therein in the form of holes or recesses,

which will in no way weaken the strength of the permanent metal socket portions.

From the foregoing it will thus be seen that I have devised a novel and improved picker stick which is particularly adapted for long wear and added strength, being especially reinforced at the points subjected to the greatest stress, in addition to presenting a construction combining the features of base rigidity and permanency with top resiliency, and having the additional advantage of quick and simple replaceability of the upper stick member in case of excessive wear or breakage of the same.

I claim:

A picker stick of the kind described, comprising an open metal frame portion and a removable wooden stick portion constructed and arranged to be wedged together, said frame having a lengthwise socket and a tapered rib formed therein, said wooden portion having a correspondingly tapered groove to interfit with the socket and rib of the metal portion, said two portions being wedgingly interlocked for a substantial lengthwise part of each.
